FIG. 4.

INVENTOR.
John A. Groeninger.

By *J. A. Groeninger*,
ATTORNEY.

UNITED STATES PATENT OFFICE.

JOHN A. GROENINGER, OF ST. LOUIS, MISSOURI.

SCAFFOLDING-FRAMEWORK CLAMP.

1,356,618.

Specification of Letters Patent. Patented Oct. 26, 1920.

Application filed December 8, 1919. Serial No. 343,330.

To all whom it may concern:

Be it known that I, JOHN A. GROENINGER, a citizen of the United States, residing at city of St. Louis and State of Missouri, have invented a certain new and useful Improvement in Scaffolding-Framework Clamps, of which the following is a full, clear, and exact description, such as will enable others skilled in the art to which it appertains to make and use the same, reference being had to the accompanying drawings, forming part of this specification, in which—

My invention has relation to improvements in clamps and consists in the novel details of construction more fully set forth in the specification and pointed out in the claims.

The object of my invention is to provide a clamp for securing together cross members of any kind of frame work and is particularly adapted to frames on which lace curtains, or anything of like character, are to be stretched.

A further object of my invention is to provide a clamp that is simple in construction and one that is easily attached and readily adjustable; other objects being better apparent from a detail description of my invention in connection with the accompanying drawings, in which—

Figure 1 represents a side elevation of a frame, the members of which are secured together by means of my improved clamp.

Fig. 2 is an enlarged view of the ends of the frame members showing the clamp applied thereto.

Fig. 3 is a face view with the clamp detached.

Fig. 4 is a side elevational view of the frame members with the clamp attached thereto, the wing nut having been removed from one of the clamping members.

Fig. 5 is a side elevation of the clamp detached.

Referring to the drawings, 1 represents the end members of a frame F, and 2 represents the side members thereof, these members being secured near their ends by means of the clamp C. The clamp C consists of a base plate 3, said base plate being provided with outwardly projecting arms 4—4 arranged at right angles to each other on the ends of which are the confining fingers 5—5', the base plate being further provided

with confining fingers 6—6', respectively, in alignment with the aforesaid fingers 5—5'.

The fingers 5—6, it will be observed are on the same side of the base plate 3 and the fingers 5'—6' are likewise on the same side of the base plate but opposite to the fingers 5—6, said fingers 5—6 constituting a series of confining members and the fingers 5'—6' also constituting a series of confining members. 65

Lugs 7—7' are bent from each of the arms 4 and opposite to the fingers 5—6 and 5'—6' with which lugs align respectively. Passing through the lugs 7—7' and secured to the arms 4 are stems 8—8' having their outer ends threaded in order that wing nuts 9—9' may be screwed thereon and mounted on said stem. Between the arms 4 and the wing nuts are complementary confining fingers 10—10', said fingers being freely slideable upon the stems 8—8' and being adjusted thereon by means of wing nuts 9—9'. 75

Stems 8—8' project beyond the arms 4 and opposite to the confining fingers 5—6, 80 5'—6' so that when the confining members 10—10' are mounted on said stems they will be oppositely disposed to the confining fingers between which they are interposed and with which they coöperate, as will 85 hereinafter be described.

In assembling a frame by means of the clamp C, the wing nut 9 is unscrewed so as to permit the confining finger 10 to be forced in a direction away from the confining fingers 5—6, thus permitting the side member 2 to be inserted in the space between the confining fingers 5—6 and intermediate confining finger 10, said fingers engaging the sides of the side member and securely confining said member against movement when the confining member 10 has been forced into engagement with the side member 2 by screwing the wing nut 9. 90 95

The end member 1 is secured to the clamp 100 in the same manner as the end member 2, it being held in place, however, by the confining members 5'—6' and 10'.

It is thus seen that a frame the members of which are secured together by the clamp C will not only be rigid but the members will also be susceptible of adjustment to and from each other, thereby regulating the size of said frame by means of the adjustable confining members 10—10'. 105

It will also be seen that by virtue of this adjustable feature, it is possible to secure members of varying width.

It is apparent that the present invention is susceptible of modifications and changes in construction which would fall within the spirit thereof, for instance, the arms 4-4, herein shown at right angles to each other, might be arranged at any angle whatever 10 according to the shape of the frame that it is desired to secure.

It will be readily understood that minor changes in the size, form and construction of the various parts of my improved scaffolding framework clamp may be made and substituted for those herein shown and described, without departing from the spirit 15 of my invention, the scope of which is set forth in the appended claims.

20 I claim:

1. A clamp comprising a base plate provided with a pair of confining members in spaced-apart relation, and an adjustable complementary confining member between 25 said pair of members and opposite thereto.

2. A clamp comprising a base plate provided with a pair of confining members and a complementary confining member interposed between said pair of members.

30 3. A clamp comprising a base plate provided with a pair of confining members, and an adjustable complementary confining member interposed between said pair of members.

35 4. A clamp comprising a base plate pro-

vided with a pair of confining members, and a complementary confining member interposed between said pair of members and opposite thereto.

5. A clamp comprising a base plate 40 provided with a series of aligned confining members, a stem secured to the base plate, and a complementary confining member mounted thereon.

6. A clamp comprising a base plate, a series of aligned confining members, a stem mounted on the base plate and projecting in a direction opposite to the confining members, and a complementary confining member 50 mounted on the stem.

7. A clamp comprising a base plate, a series of aligned adjustable complementary confining members, a stem mounted on the base plate and projecting in a direction opposite to the confining members, and a complementary confining member 55 mounted on the stem.

8. A clamp comprising a base plate provided with outwardly projecting arms angularly arranged, said arms having confining members on their extremities, confining 60 members on the base plate adapted to cooperate with the confining members on the arm, stems secured to the base plate and projecting outwardly from the arms, a complementary confining member on each stem, 65 and means for adjusting said complementary confining member.

In testimony whereof I hereunto affix my signature this 6th day of December, 1919.

JOHN A. GROENINGER.
